US0D1051943S

(12) **United States Design Patent** (10) Patent No.: **US D1,051,943 S**
(45) Date of Patent: ** Nov. 19, 2024

(54) **DISPLAY SCREEN OR PORTION THEREOF
WITH GRAPHICAL USER INTERFACE**

(71) Applicant: **Caterpillar Inc.**, Peoria, IL (US)

(72) Inventors: **Ramya Gangishetty**, Dunlap, IL (US);
Keith Folken, West Peoria, IL (US);
Russell Loring Stott, Chapin, SC (US);
Varun K. Yellichetty, Irving, TX (US);
Patrick Aaron Cozad, Canton, IL (US);
Rajendra Behara, Bangalore (IN); **Jennifer Heine**, Mannheim (DE)

(73) Assignee: **Caterpillar Inc.**, Peoria, IL (US)

(**) Term: **15 Years**

(21) Appl. No.: **29/866,500**

(22) Filed: **Sep. 15, 2022**

(51) LOC (14) Cl. **14-04**

(52) U.S. Cl.

USPC **D14/485**

(58) **Field of Classification Search**

USPC D14/485-495

CPC G06F 3/048-04897

See application file for complete search history.

(57) **CLAIM**

The ornamental design for a display screen or portion thereof with graphical user interface as shown and described.

DESCRIPTION

The sole FIGURE is a front view of a display screen or portion thereof with graphical user interface showing our new design.

The peripheral dashed broken lines depict a display screen or portion thereof, and form no part of the claimed design.

1 Claim, 1 Drawing Sheet
